EARTH ANCHOR

Chester R. Pieper, Ladue, St. Louis County, Mo.

Application October 19, 1951, Serial No. 252,124

2 Claims. (Cl. 189—92)

1
This invention relates to improvements in earth anchors, and more particularly to improvements in an expansion device of this character which presents a four lobed expansion type anchor of simplified, highly durable construction and relatively low manufacturing cost.

An important objective realized by the anchor assembly is in the novel operative interconnection of two double lobed blade members. Each blade member includes two earth-gripping blades or lobes connected by an integral intervening metal plate. These blade members are so constructed and arranged that one is capable of overlying the other, with the longitudinal axes of the respective blade members disposed in right angular relation. The nested or underlying blade member provides opposed ears or lugs which extend upwardly from the lateral margins of the connecting metal plate, the lugs projecting through accommodating apertures formed in the intervening plate portion of the overlying blade member, and bending inwardly to positively grip and position the lobes in a right angle relation. These lugs afford percussion surfaces that receive the blows of the tampering tool. When the folded assembly is inserted in the pre-formed hole, these ears will continue to lock the blades in their proper relative alignment as they are spread or distended into gripping relation with the surrounding soil.

The objects above expressed and others implied from the description to follow will become more readily apparent from the following detailed description of a single preferred embodiment, particularly when considered in connection with the accompanying drawing, in which:

Fig. 1 is a top plan view of the earth anchor assembly, the blade members thereof in their folded position;

Fig. 2 is a sectional view of the anchor assembly as seen in a plane taken along line 2—2 of Fig. 1; the dotted lines represent the blade members in their spread or extended positions;

Fig. 3 is a sectional view of the anchor assembly as seen in a plane taken along line 3—3 of Fig. 2; and

Fig. 4 is a perspective view of the connecting integral metal plate and web portions of the nesting and overlying blade members respectively.

Referring now by characters of reference to the drawing, it is readily apparent from Fig. 1, that the four blade type expansion earth anchor assembly includes a pair of double lobe blade members. Each blade member consists of two earth-gripping blades or lobes 10 connected by an in-

2
tegral intervening metal plate 11, and is preferably stamped from a single blank of relatively heavy gauge sheet metal material.

These blade members are so designed and arranged that in folded assembly, as shown in Figs. 1, 2 and 3, they are nested, one overlying the other, but disposed in such position that the respective longitudinal axes thereof are in a right-angle relation. Referring again to Figs. 2 and 3, the connecting plate portion 11 of the blade members, which are in the folded, non-gripping or initial assembly, presents a substantially flat horizontal surface with the depending lobes 10 extending downwardly, the arcuate outer edges 12 thereof seating upon the rounder peripheral edge 13 of the blade-expanding member, designated generally at 14 and described more fully later.

The connecting integral metal plate of the nested or under blade member 15 contains a circular aperture 16 at the intersection of the transverse and longitudinal axes thereof, accommodating the reception of the anchor rod 17. Two ears or lugs 18 are formed from the lateral margins 19 of the plate portion and project upwardly through compatible ear receiving slots 20 formed in the rounded connecting region of the plate 11 and lobes 10 of the overlying blade member 21. This latter plate portion also contains a circular aperture 22 in its central zone, in register with that formed in the underlying blade member 15, for the insertion of the anchor rod 17. Two rectangular openings 23 are stamped in the overlying plate member, one on each side of the anchor rod aperture 22 through and symmetrical with the transverse axis of the blade member 21, substantially reducing the cross sectional area along the axis. These rectangular openings 23 are so situated that there remains only a small metal area between the inner edges 24 thereof and the circular aperture 22, while relatively considerably more area exists between the outer edge 25 thereof to the lateral margins of the web plate member.

Each blade or lobe 10 is curved such that its outer arcuate edge 12 is directed upwardly relative to the center zone thereof, and each contains a relatively deep pressed rib 26 extending along the longitudinal axis, the rib 26 strengthening the lobes 10 against transverse bending stresses. The margins of the overlying blade member 21, connecting the outer arcuate edges 12 thereof, have a slight inward curving leading from the arcuate tip 12 merging with an outwardly and upwardly turning flange 27 formed along each side of ap-

proximately the upper one-half portion of the

blades 10. The margins, connecting the arcuate edges 12 of the underlying blade member 15, converge upwardly to the integral intervening plate portion. The lobes 10 of the latter blade member 15 also contain outwardly turning flanges 28 in the same region as do the blades 10 of the overlying member 21. The existence of these flanges in the respective blade members permits the shown and described interfitting relation, and yet provides the maximum amount of earth-gripping blade area.

The strain plate 14 is stamped from a blank of heavy gauge material, and is provided with a circular aperture 23 in the central zone thereof which permits the insertion of the anchor rod 17. A flat horizontal area 30 immediately surrounds the anchor rod opening 29, the remaining upper surface 31 of the spreading element 14 slopes downwardly from the central horizontal area 30 to a rounded down-turned peripheral flange 32 adapted to guide and direct the lobes 10 into distended earth engaging positions upon tamping of the anchor. A wire 33 is inserted through an opening 34 in the outermost portion of the arcuate tip 12 of each lobe 10, through corresponding openings 35 near the periphery of the strain plate 14, and is twisted to lock the blade members in folded assembly, until sheared free by the initial blows of the percussion tool.

Secured as by welding to the underneath surface of the blade-spreading member 14, around the anchor rod aperture 29, is a nut retaining element 36. The nut retainer 36 contains two different cross sectional compartments as shown in Figs. 2 and 3, the wall of the larger upper portion 37 rounding slightly into the smaller lower portion 38. This construction will permit various size nuts to be used depending upon the size anchor rod 17 employed. The lower surface of the nut retainer 36 contains a circular opening 39 through which the rod 17 extends, and is also provided with small downwardly turning lips 40 depending from the circular opening 39, the lips 40 providing a bearing surface for the rod 17 preventing excessive wobbling thereof. The rotational movement of the enclosed nut is prevented by the nut retainer 36, thereby permitting the removal of the anchor rod 17 while the anchor is in its spread operative position under ground.

The initial assembly of the anchor is shown by the drawing, the blade members folded in the zone of the connecting integral plate members 11. The blade member 21 containing the web plate, overlies the other member 15, being so disposed that the respective longitudinal axes are in a right angular relation. The lower arcuate tips 12 of the blades 10 seat upon the peripheral edge of the strain plate 14 and are locked in position by the inserted twisted wire 33. An anchor rod 17 is inserted through the uppermost circular apertures and through the rod opening 29 in the spreading element 14, to be threadedly engaged by the nut contained in the nut retainer.

For use in the field, a hole of desired depth is formed in the ground, and the anchor assembly is inserted therein. A suitable tamping tool is employed to strike the horizontal connecting web portion of the overlying blade member 21. The initial tamping blows shear the wire and commence the penetration of the blades 10 into the surrounding earth.

Although the improvements have been described by making particularized reference to a single preferred embodiment, the detail of description is not to be understood as restrictive, numerous variants being possible within the principles disclosed and within the fair scope of the claims hereunto appended.

I claim as my invention:

1. An expansion earth anchor comprising two blade members, each thereof being integrally formed and providing a pair of earth-engaging lobes and an intermediate portion or plate defined between spaced transverse bending zones, said blade members being arranged with their longitudinal axes in right angular relation and with the plate of one superimposed upon the plate of the other, the width of the underlying plate being appreciably less than the width of the overlying plate, and substantially equal to the distance between the bending zones of the overlying plate, said overlying plate having slotted openings in its said bending zones, said underlying plate having integral ears projecting from its side margins and extending through said slotted openings for securing said plates together, said plates having aligned central openings therein, an anchor rod extending through said opening, and a strain plate secured to the lower end of said anchor rod and engaging the under surfaces of the blade lobes.
2. In an expansion earth anchor of the four blade type, a pair of blade members formed from elongate metal stampings, said blade members arranged in respective underlying and overlying positions, having the longitudinal axes thereof disposed in a right angle relation, opposed lobes defining the end portions of the blade members, an intervening web portion integrally connecting the lobes of the overlying member, the said web containing a circular central aperture for the reception of the anchor rod and rectangular apertures on each side thereof through the transverse axis of the blade member substantially reducing the cross sectional area along the said axis, thereby permitting a transverse concave depression to be formed upon tamping of the anchor, a plate portion of reduced width integrally connecting the lobes of the underlying blade member, said plate having a circular central anchor rod aperture, opposed ears projecting from the lateral margins of the said plate, compatible ear receiving slots formed substantially within the merger zone of the said lobes and web of the overlying blade member, said ears extending through said slots and being bent inwardly upon said web, and a strain plate having an outwardly and downwardly sloping surface extending from a horizontal central region and a down-turned peripheral flange, said strain plate being adapted to guide and spread the lobes into expanded earth gripping positions.
